UNITED STATES PATENT OFFICE.

GERHARD C. KLEWER, OF CHICAGO, ILLINOIS.

TABLET-MAKING MACHINE.

No. 839,157.

Specification of Letters Patent.

Patented Dec. 25, 1906.

Application filed August 8, 1904. Renewed October 29, 1906. Serial No. 341,130.

To all whom it may concern:

Be it known that I, GERHARD C. KLEWER, a citizen of the United States, and a resident of Chicago, in the county of Cook and State of Illinois, have invented certain new and useful Improvements in Tablet-Making Machines, of which the following, when taken in connection with the drawings accompanying and forming a part hereof, is a full and complete description, sufficient to enable those skilled in the art to which it pertains to understand, make, and use the same.

This invention relates to tablet-making machines, whereby a large number of tablets of a given size and shape are desired to be made; and the object of this invention is to obtain a tablet-making machine by means of which a large number of tablets of a determined size and density may be made, and, further, to obtain a machine which can be readily and quickly changed when making a tablet of one size and shape to make a tablet of a different size and shape or of a different size and by means of which when the machine is changed a large number of tablets of the new size and shape and of the desired density may be quickly made.

A further object of the invention is to obtain a tablet-making machine which is not liable to get out of order, which is not expensive in construction, and which is durable.

In the drawings hereinbefore referred to, Figure 1 is a front elevation of a tablet-making machine embodying this invention. Fig. 2 is a vertical sectional view of a cylinder provided with annular flanges, showing one each of an upper and a lower series of plungers in such flanges. Fig. 3 is a top plan view of a little more than one-half of the base of the machine. Fig. 4 is a vertical sectional view of the base of the machine on line 4-4 of Fig. 3 viewed in the direction indicated by the arrows. Fig. 5 is an elevation of a section of a horizontal bar which is mounted so as to be vertically movable on the vertical standards of the machine. Fig. 6 is a top plan view of the section of the horizontal bar which is illustrated in Fig. 5; and Fig. 7 is a perspective of an adjustable thimble and nut, shown also in Fig. 2, forming an element in the machine embodying this invention. Fig. 8 is an elevation of a part of one of the upper series of plungers with a collar

and spring thereon to yieldingly maintain 55 the plunger in a retracted position.

A reference-letter applied to designate a given part is used to indicate such part throughout the several figures of the drawings wherever the same appears.

A is the base of the machine and comprises the square portion *a* and the cylindrical portion *a'*.

B B are vertical standards (which are preferably round) fitted firmly in holes B' B' of 65 the base A. (See Figs. 3 and 4.)

C is a horizontal table mounted to be moved vertically on standards B B and arranged to be secured by means of the set-screws C² C² in an adjusted position. (See Fig. 1.)

D is a horizontal bar mounted on the standards B B by means of holes in the ends D' D' thereof fitting over the standards B B. Such horizontal bar D may be moved vertically to 75 an adjusted position and there secured by the set-screws D² D². E is a horizontal bar also mounted on the vertical standards B B. The ends E' E' of bar E are provided with holes E² E², (see Figs. 5 and 6,) respectively, 80 such holes fitting over the vertical standards B B in a manner to permit vertical movement of the bar on the standards.

F F are compression-wheels rotatably mounted on horizontal bar E. This bar E is 85 preferably built up (in the manner illustrated in Figs. 5 and 6) of the part *e*, the rods or axles *e' e'*, and ends E' E'. The part *e* is provided with hole *e²*, through which the vertical shaft G extends, and with hole O², through 90 which an adjusting-bolt, hereinafter described, extends. The axle or rod *e'* extends into the part *e* and into the part E' in the manner indicated by the dotted lines in Figs. 5 and 6 and is firmly secured in place, as by 95 the rivets *e³ e³*.

The vertical shaft G may be provided with the ball-bearings *g* at the lower end thereof, if desired. The upper end of the shaft G extends through the horizontal bars D and E 100 and rotates therein.

H is a cylinder on shaft G.

The shaft G is provided with the shoulder *g'* thereon, (see Fig. 2,) and the cylinder H is provided with a hub *h*, having a hole therein 105 fitting on the smaller part of the vertical shaft G, so that such cylinder rests on the shoulder *g'*, as is illustrated in Fig. 2 of the

drawings. Cylinder H is secured rigidly to the shaft G to turn therewith, as by the feather I. (See Fig. 2.) Cylinder H may be removed from vertical shaft G whenever desired by removing the horizontal bars D E from vertical standards B B and removing the feather or spline I from shaft G, and such cylinder may be replaced by another cylinder, (a duplicate thereof,) in which the dies about to be described are of a different size or shape from those on the first-named cylinder.

h' is an annular flange which may be and preferably is integral with cylinder H.

h^2 h^2 and h^3 h^3 are annular flanges fitted rigidly onto the cylinder H. (See Fig. 2.)

J J, J' J', and J² J², respectively, are holes in the annular flanges of cylinder H.

K K are plungers in holes J J', and K' K' are plungers in holes J² J². Plungers K K are hereinafter referred to as the "lower" series of plungers, and plungers K' K' are hereinafter referred to as the "upper" series of plungers. In the several plungers of the lower series there are placed punches L L, and in the several plungers of the upper series there are placed the dies L' L'. The several dies are firmly secured in place, as by the set-screws l l.

M is a die in one of the holes J J of flange h' .

m is the hole in die M. (See Fig. 2.)

When the several parts of the machine are all assembled, there is a die M in each one of the holes J, and a plunger containing a punch is mounted in each set of holes J J' and J² J².

The lower series of punches L L are set in the lower series of plungers K K, so as to be in the die M (see Fig. 3) when at the lowest possible position of such punches, and the thickness of the tablet compressed by this machine is determined by the position of the upper end of such punches L L when in such lowest possible position, and hence in order to make tablets of different thickness in the machine I make the position of the plungers K K adjustable longitudinally, as by means of a thimble N, Figs. 2 and 7, mounted thereon and provided with screw-threads n therein. Screw-threads n in the thimble N intermesh with screw-threads n' on the plungers K.

N² is a slot in thimble N. This slot when used is made before the screw-threads n are cut in the thimble, and thereby such screw-threads fit sufficiently close to the plunger K to prevent the same from turning from an adjusted position.

N³, Fig. 2, is a spring on plunger K. The upper end of spring N³ abuts against the under side of the upper one of the annular rings h^2 , and the lower end of such spring rests on the shoulder n³, obtained by placing the head n⁴ on thimble N. The spring N³ on plunger K tends to yieldingly hold such plunger down, so that the head n⁴ of the thimble N thereon rests on the upper face of the lower one of the annular flanges h^2 .

N⁴ is a spring on plunger K', tending to hold such plunger up—that is, in a retracted position—in the same manner as spring N³ tends to yieldingly hold the plunger K down in a retracted position.

N⁵ is a collar on the plunger K', corresponding in function with the thimble N on plunger K, and N⁶ is a set-screw by means of which collar N⁵ is maintained in an adjusted position.

The quantity of material deposited in the hole m of the die M is determined, as hereinbefore stated, by the adjustment of plunger K, which is obtained by thimble N, as described, and to obtain the movement to plunger K' and die L', mounted therein, required to give the density required to the tablet made in such die M, I provide the adjustments and connections between the bars D and E, which I will now describe.

O O are set bolts or screws extending loosely through bar D and provided with screw-threads O' at the lower end thereof, intermeshing with corresponding screw-threads in hole O' of bar E.

P P are nuts on bolts O O, such nuts being provided with threads which intermesh with threads O' O', and Q Q are springs on bolts or screws O O.

Bar D is secured rigidly on standards B B by means of set-screws D² D². Adjusting-bolts O O are then turned and bar E thereby forced down, so that the wheels F F depress the several plungers K' K' passing thereunder to give the desired thickness to the tablet made in hole m of die M. The bar E is thus yieldingly held in its adjusted position by means of the lock-nuts P P and springs Q Q—that is, the tendency of the bar E to be forced up by the passing of the several plungers K' K' thereunder in the revolution of the shafts G and cylinder H is opposed by the springs Q Q—and it thus occurs that in order to obtain a given density to the tablet made in hole m a determined adjustment of the lock-nuts P P on bolts O O relative to the springs Q Q is required. The more the nuts P P are forced against such springs Q Q the greater is the resistance offered by such springs to any upward movement of the horizontal bar E.

R is a thin cylindrical covering—say of sheet metal—over the annular flanges h^2 h^2 and h^3 h^3 , respectively, merely to prevent dust settling on the respective plungers in such flanges.

To force the plungers K K up after a tablet has been made in die M, the wheels S S, Fig. 1, are provided. The several plungers are raised as they are carried over such wheels by the rotation of the cylinder H.

To supply material from which tablets are to be made to the hole m of die M, I provide a hopper T, with pipe U depending therefrom and the extension V at the lower end thereof. Such extension V rests on table C.

The several dies L' L' pass over the extension V in the revolution of the cylinder H, as is shown in Fig. 1, and the hole m is filled by the material contained in hopper T, depending pipe U, and extension V, and when the respective dies M come out from under the extension V they are filled with material which is compressed when the punch L' there-over is depressed by the plunger in which such punch is held, passing under the adjacent one of the depressing-wheels F F.

In this machine there are made at each revolution of the cylinder H two tablets for each pair of plungers (an upper and a lower one) in the respective annular rings on such cylinder, one of such tablets being made as the upper plunger of a pair passes under one of the wheels E E and the other of such tablets made as such plunger passes under the other one of such wheels E E.

Having thus described my invention, what I claim as new, and desire to secure by Letters Patent, is—

1. The combination of vertical standards, a rotatably-mounted vertical shaft, a cylinder provided with annular flanges rigidly secured on the shaft, an upper and a lower series of longitudinally-movable plungers mounted on the annular flanges, means to force the plungers of the lower series up a plurality of times at each revolution of the cylinder and mechanism to force the plungers of the upper series down a corresponding number of times in the revolution of the cylinder, such mechanism to force the plungers of the upper series down consisting of a horizontal bar vertically movable on the vertical standards, wheels rotatably mounted on the horizontal bar in the path of movement of the upper ends of such plungers, an additional horizontal bar removably secured on the vertical standards and an adjustable yielding connection between the horizontal bars; substantially as described.

2. The combination of a base, vertical standards on the base, a rotatably-mounted vertical shaft provided with a shoulder thereon, a cylinder provided with annular flanges removably placed on the shaft to rest on the shoulder and to turn with such shaft, an upper and a lower series of longitudinally-movable plungers mounted on the annular flanges, means to force the plungers of the lower series up a plurality of times at each revolution of the shaft and cylinder and mechanism to force the plungers of the upper series down a corresponding number of times in the revolution of the shaft and cylinder, such mechanism to force the plungers of the upper series

ries down consisting of a horizontal bar vertically movable on the vertical standards, wheels rotatably mounted on the horizontal bar in the path of movement of the upper ends of the plungers, an additional horizontal bar removably secured on the vertical standards, and an adjustable yielding connection between the horizontal bars; substantially as described.

3. In a machine for pressing tablets provided with longitudinally-movable plungers mounted on a rotatable cylinder, the combination of means to force the plungers of a lower series up a plurality of times at each revolution of the cylinder with means to force the plungers of an upper series down a corresponding number of times in the revolution of such cylinder, the means applied to force the plungers of the upper series down comprising a horizontal bar, wheels mounted on the horizontal bar in the path of movement of the upper ends of the plungers of such upper series, a second horizontal bar, means to secure the second-named bar in an adjusted position, and an adjustable yielding connection between the horizontal bars; substantially as described.

4. The combination of vertical standards, a vertical shaft, a cylinder on the shaft, flanges on the cylinder, plungers in the flanges, means to move the plungers longitudinally a plurality of times at each revolution of the cylinder, horizontal beams, one thereof rigidly secured to the vertical standards and one thereof vertically movable on such standards, bolts extending through the rigidly-attached horizontal beam, screw-threads on the bolts and screw-threads intermeshing therewith in holes in the vertically-movable beam, springs on the bolts, means to vary the tension of the springs, and wheels rotatably mounted on the vertically-movable beam to engage with the upper series of plungers; substantially as described.

5. In a tablet-making machine a plunger consisting of a longitudinally-movable body part, a thimble adjustably secured on such body part, such thimble provided with a shoulder thereon, and a spring on the bolt, in combination with a plurality of annular rings against one of which rings the thimble is forced by one end of the spring coming in contact with the other ring, and a rotatably-mounted cylinder on which the rings are mounted; substantially as described.

GERHARD C. KLIEWER.

In presence of—

LEON J. CAMPBELL,

CHARLES TURNER BROWN.
